UNITED STATES PATENT OFFICE.

JOHN URI LLOYD, OF CINCINNATI, OHIO.

VIAL OR MEDICINE-BOTTLE.

SPECIFICATION forming part of Letters Patent No. 628,269, dated July 4, 1899.

Application filed August 10, 1898. Serial No. 688,254. (No model.)

To all whom it may concern:

Be it known that I, JOHN URI LLOYD, a citizen of the United States, and a resident of Cincinnati, in the county of Hamilton and 5 State of Ohio, have invented certain new and useful Improvements in Vials or Medicine-Bottles, of which the following is a specification.

My invention relates to an improved medicine-vial. Its object is a vial or bottle from 10 which liquid may be poured readily in drops.

Figure 1 is a side view of a vial embodying my invention. Fig. 2 is a similar view of a modified form thereof.

15 In Fig. 1 the body A is curved a short distance below the mouth a to bring the part between the mouth and the curve at an angle to the part between the curve and the bottle, so that in dropping the liquid in the lower 20 part of the bottle exerts no force that could interfere with the gradual and even dropping of the liquid from the mouth.

In the modification shown in Fig. 2 there is a pocket a' formed in the inner curve to receive a small quantity of liquid when the vial 25 is inclined and insure a more even dropping from the mouth.

What I claim is—

1. An open-mouth vial bent at an angle a short distance from its mouth, and adapted 30 to gradually and evenly deliver its contents in the form of drops, substantially as shown and described.

2. The hereinbefore-described open-mouth vial having its upper part formed at an angle 35 to the lower part and having a pocket formed in the inner side of the curve joining the parts, and adapted to deliver its contents in the form of drops.

JOHN URI LLOYD.
